UNITED STATES PATENT OFFICE

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH

Application filed May 31, 1930. Serial No. 458,872.

This invention relates to heavy duty electric switches and improved actuating mechanisms for these switches.

The switch embodying this invention comprises a plurality of separate switch units having their operating mechanism interconnected for conjoint operation, and it is an object of the invention to provide a single improved actuating mechanism common to all of said units for mechanically and also electrically closing the switches and also for tripping the switches electrically.

It is a further object of the invention to provide an improved power-operated actuating mechanism for the control of multi-phase heavy duty switches.

A yet further object is generally to improve the construction and operation of electric switches and control mechanism therefor.

Fig. 1 is a front elevation of a three phase switch having the actuating mechanism of the invention associated therewith.

Fig. 2 is a side elevation of the actuating mechanism associated with the middle unit of Fig. 1.

Fig. 3 is a plan view showing the coil box for the switch closing solenoids.

Fig. 4 is a diagrammatic view of the electrical connections for the switch closing solenoids.

The electric switch herein shown is adapted to control a three phase power circuit and comprises three similar switch units. Each unit includes a substantially cylindrical switch frame 10 which forms a cover for an oil receptacle 12 which is received within and depends below said switch frame. A cradle 14 is secured, as by welding, to the bottom of said oil receptacle and provides a bottom closure therefor. Each switch frame 10 also comprises a support for a pair of stationary switch members including the insulating bushings 16 and axial conducting studs 18 which extend through the top of said switch frame and depend into the oil within the receptacle 12 in the usual manner. Said studs 18 are provided at their lower ends with stationary contact members, not shown.

Each switch frame 10 also is formed with a

forwardly extended mechanism compartment 20 which terminates in a vertical front face or platen 22 which provides a support for a vertical panel 24. The mechanism compartment 20 of each unit has suitable switch mechanism contained therein by which a movable switch member, not shown, is reciprocated into and out of engagement with its cooperating stationary contact members to complete and interrupt the circuit through the switch. Said switch mechanism includes a horizontal shaft 26 which is extended through a side wall of compartment 20 and has fixed thereto exteriorally of the compartment the depending crank arm 30.

The several switch units, as shown in Fig. 1, are located in adjacent cell compartments A, B and C with their operating mechanisms interconnected for conjoint operation. The switches are supported in elevated position in the cells by means of horizontal channels 32 which are located at the front and back of each unit and which are connected by means of stay bolts 34. Said channels 32 are supported at their ends by pairs of channels 36 placed back to back, which are embedded in the walls 38 between adjacent cells. Said channels 36 have welded thereto angular attaching clips 40 which are secured by bolts 42 to the backs of channels 32, whereby to secure said channels fixedly in place. Bolts 44 are provided to secure the switch frames 10 removably to the front channel members 32.

The switch mechanisms of the several switch units, as represented by the crank arms 30, are adapted to be interconnected through suitable operating mechanism for conjoint operation and, to this end, each unit is provided with an operating face plate 46 which is secured to the panel 24 by means of bolts 48 which are passed through said face plate and each panel and the platen 22 of the mechanism compartment 20. Each face plate 46 is provided, at its upper end, with pairs of horizontally-spaced forwardly-extended arms 50 at the extended ends of which is journaled a section 52 of a horizontal switch operating shaft. Said sections 52 are arranged in axial alignment and are

operatively connected at their adjacent ends by interlocking coupling members 54 which are arranged to provide for conjoint rotation of the sections, even though they should be 5 axially displaced. Each section 52 has fixed thereto a depending crank arm 56 which is pivotally connected by means of an adjustable link 58 with the crank arm 30 of the associated switch unit. Thus, it will be evident 10 that the rotation of the operating shaft including the sections 52 of the several switch units will effect a simultaneous movement of the crank arms 30 of the several switch mechanisms to open and close all the units of the 15 switch conjointly.

A single actuating mechanism is provided which is adapted to be both manually and electrically operated to open and close the switch. To this end, the face plate 46 of 20 the middle unit, as viewed in Fig. 1, is provided with forwardly extended side portions 60 which are provided with a second pair of horizontally spaced forwardly extended arms 62. Said arms 62 have journalled therein at their forward ends an actuating shaft 64 which is disposed beneath and parallel with the section 52 of the operating shaft. The face plate 46 is further provided with a lower horizontal shelf 66 which is cast integral 25 therewith and which provides a support for the switch closing solenoids, hereinafter to be described.

Said actuating shaft 64 has fixed thereto an actuating member 68. Said actuating member includes a pair of forwardly extended arms 70 which converge at their extreme forward ends to provide short closely spaced parallel attaching portions 72 between which is received a vertical link 74 which is 30 pivotally connected at its lower end to said arms by a pin 76. Said link is pivotally connected at its upper end by a pin 78 with a forwardly extended crank arm 80 which is rigidly fixed to the operating shaft 52 and 35 which is angularly related to the crank arm 56. The operating shaft 52 and the crank arms 80 and 56 constitute in effect an operating bell crank lever.

Means are provided for actuating said actuating member 68 electrically whereby to effect the closing of the switch. Said means includes a substantially rectangular iron coil box 82 closed at the top and open at the bottom, which is formed with four horizontally aligned vertically disposed cylindrical compartments 83, 84, 85 and 86, each of which is adapted to receive a separate switch closing solenoid. Said coil box is secured removably by means of cap screws 87 to the 50 lower face of shelf 66 in such position that the vertical axes of the several compartments occupy a vertical plane which is parallel with but is somewhat to the rear of the vertical plane including said actuating shaft 64. 55 Rectangular plates 88 are secured by means

of bolts 90 to the open bottom of said coil box whereby to provide separate closures for each of said solenoid compartments. Each solenoid includes a cylindrical winding 91 and a central operating plunger, or armature, 70 92. The operating plunger 92 of each solenoid extends through a passage 93 in the top wall of its compartment and is operatively connected with the actuating shaft 64 by means of a pair of similar studs, or eye bolts, 75 94 which are separately screw threaded at their lower ends into the plunger and which are provided at their upper ends with parallel flared end portions having eyes through which a pin 96 is extended. The plungers of 80 the several solenoids are pivotally connected by said pins 96 with rearwardly extended crank arms 98, which crank arms are fixed to the actuating shaft 64 at spaced intervals therealong in position to lie between the 85 spaced studs of the several solenoid plungers. The crank arms 98 connected with the two middle solenoids are formed as an integral part of the actuating member 68, the outer crank arms being carried by the actuating shaft 64 near the ends thereof. It will be evident that if the switch is open and the solenoids in the coil box 82 are energized, the actuating member 68 will be rotated in a clockwise direction, as viewed in Fig. 2, thus 90 to move the operating bell crank including the crank arms 80 and 56 in a clockwise direction, due to the link 74 connecting the two, and the switch mechanism of the several switches will be moved into the closed position of Fig. 2, wherein the plungers 92 of the solenoids will be in engagement with core plugs which upstand above the bottom plates 95 88.

Means are provided to latch the actuating 100 mechanism in a switch closed position. To this end, the right hand crank arm 98 of the actuating member 68, as viewed in Fig. 1, is provided with an integral extension 100 which has a toggle link 102 pivotally connected thereto by a pin 104 which passes through a yoke 105 of said toggle link. Said yoke has threaded thereinto an adjustable eye bolt 106 having an eye 108 at its free end. Said eye bolt 106 is pivotally connected by 115 means of a pin 110 between the bifurcations of the end-portion 112 of a crank arm 114 which is loosely mounted on the operating shaft 52 between a fixed thrust collar 116 and the right hand forwardly extended bearing arm 50, as viewed in Fig. 1. Said arm 114 and the link 102 constitute a toggle which is adapted in the switch closed position of the mechanism to occupy an underset position, as shown in Fig. 2. Said toggle is constantly biased toward a collapsed position by the switch operating mechanism and also by a spring 118 which is fixed to a lug 119 of said face plate at one end and has its other end fixed to a pin 96 of one arm 98 of said ac- 120 125 130

tuating shaft, whereby constantly to urge the counterclockwise rotation of the switch operating and switch actuating shafts into the switch open position thereof. Said locking 5 toggle is adapted to be held releasably in the aforesaid underset position, whereby to hold the switches closed, by means of a latch 120 which is pivotally mounted on a pin 122 between the bifurcations 124 of an upstanding 10 arm 126 which is formed integral with the bottom horizontal shelf 66. To this end, the toggle link comprising arm 114 has formed integral therewith an angularly related depending latch arm 130 which is offset to the right as viewed in Fig. 1, and terminates in a forwardly curved end portion which in the closed position of the switch is adapted to lie just back of the actuating shaft 64 in the same vertical plane with said latch 120. 15 Said latch arm is bifurcated at its lower end and has a latch roller 132 which is pivotally mounted between the bifurcations thereof on a pin 134, which roller is adapted to be engaged and held by the vertical latch face 136 of latch 120, thus to lock the toggle releasably in set position, in which the switch is closed.

A tripping coil 138 is secured to the front face of said coil box beneath the forwardly extended latch 120 and has its plunger 140 operatively connected by a pin 142 with a pair of links 143. Said links are formed with vertically-elongated slots 144 in which a pin 145 carried by the forwardly projecting end of latch 120 is freely movable. The lower end 146 of said slots are adapted to engage pin 145 when said tripping solenoid is energized to raise the plunger 140, whereby to trip the latch and permit the switch to open. 20 The latch can be depressed free from said plunger 140 when the switch is closed by reason of said slots 144.

The switch also can be opened or tripped manually by raising the forward end of the latch.

The switch is also arranged to be closed manually. The closing means for the switch includes a horizontal shaft 148 which is disposed above and is perpendicular to the operating shaft 52 and is journaled in a pair of spaced upstanding bearings 149 and 150, which bearings are formed integral with the right hand side portion 50 of the face plate 46. Said shaft is provided with a pinion gear 151 having spiral gear teeth which mesh with spiral gear teeth 152 which are cut in a portion of the periphery of the hub 154 of crank arm 114. The forward end of shaft 148 is provided with diametrically opposite flat faces 155 which are adapted to be engaged by the hub of a suitable lever, not shown, for rotating the shaft manually. A fixed collar 156 on said shaft provides a limit stop against which the hub of the manual lever is 25 adapted to rest, and the gear and a collar

which are disposed on opposite sides of the upstanding bearings 149 prevent axial movement of the shaft due to the thrust of the spiral teeth of said pinion.

It will be evident from Fig. 2 that when the switch is latched in closed position the elevation of the forward end of the latch, either electrically or manually, will permit the toggle 114, 102 to collapse and, under the action of spring 118, will permit the actuating member 68 to rotate in a counterclockwise direction. Movement of the actuating member 68 in a counterclockwise direction will also effect a counterclockwise rotation of the operating bell crank including arms 80 and 56 which are fixed to the operating shaft 52, thus to open all of the switch units jointly.

If now it is desired to close the switch manually, the manual operating lever, not shown, is placed on the forwardly extended end of shaft 148 and is moved to rotate said shaft in a counterclockwise direction as viewed in Fig. 1 whereupon the arm 114 is rotated in a clockwise direction, Fig. 2, thus nearly to straighten the toggle 114, 102 which now constitutes an actuating toggle, and effect closing movement of the switch through the actuating member 68, link 74, and operating bell crank 80, 56.

By the provision of the coil box 82 with the four separate solenoids therein, applicant is enabled to provide a compact and powerful switch closing solenoid that can close three or more switch units rapidly. As shown diagrammatically in Fig. 4, the four solenoid windings 162, 163, 164, 165 are connected in parallel with leads 166 and 170 of the battery 172 or other source of power and are actuated by closing the remote control switch 174, all of the coils acting in unison through the single actuating mechanism above described. This construction of the closing solenoids is more fully described and claimed in my copending application Serial No. 458,187, filed May 31, 1930 and need not be further described.

The operating shaft 52 of the end switch units are each provided with downwardly and forwardly extended crank arms 176 which are rigidly fixed to the shaft. A rod 178 is pivotally connected with the end of said arm and is extended through a passage 180 in the upper closed end of a cylinder 182. Said rod 178 is provided at its lower end with a disc 184 located within said cylinder, and a helical compression spring 186 is disposed between said disc and the top wall of said cylinder. Said cylinder 182 is provided at its lower end with a pair of depending ears 188 which are pivotally secured by a pin 190 to a lug 192 carried by the front face of the operating face plate 46. In the switch closed position of the operating shaft 52 and arm 176 the spring 186 is compressed, where-

by to bias the operating mechanism of the end switch units constantly toward an open position.

Various modifications may be made in the arrangement of the mechanism without departing from the scope of the invention.

Certain features herein shown are also described in my copending application Serial No. 458,871, filed May 31, 1930.

10 I claim:

1. Electric switch operating mechanism including the combination of a switch operating member, a pivoted actuating member having a rigid link pivotally connecting said

15 actuating and operating members, a locking toggle having one end thereof pivotally connected with said actuating member and having its other end pivotally connected to a fixed support, a latch arm carried by one of said toggle members, a latch for engaging said latch arm whereby to hold said toggle releasably in an underset position, means to trip said latch electrically, and manual means for operating said actuating

20 member to close the switch including a manually operable shaft, a pinion carried by said shaft, and cooperating gear teeth carried by one of said toggle members.

25 2. Electric switch operating mechanism including the combination of an operating shaft, switch opening and closing mechanism including an actuating shaft, an actuating member fixed to said shaft and having oppositely directed arms, a rigid link oper-

30 atively connecting one of said arms with said operating shaft, a switch closing mechanism operatively connected with the other of said arms, means to hold said operating mechanism releasably in switch closed position including a locking toggle having one end thereof pivotally connected with an arm of said actuating member and having its other end pivotally supported on said operating shaft, a latch arm carried by one mem-

35 ber of said toggle, a latch arranged to engage said latch arm to hold said toggle releasably in an underset position, and means for tripping said latch.

40 3. Electric switch operating mechanism including the combination of an operating shaft, switch opening and closing mechanism including an actuating shaft, an actuating member fixed to said shaft and having oppositely directed arms, a rigid link oper-

45 atively connecting one of said arms with said operating shaft, means to hold said operating mechanism releasably in switch closed position including a locking toggle having one end thereof pivotally connected with an arm of said actuating member and having its other end pivotally supported on said operating shaft, a latch arm carried by one mem-

50 ber of said toggle, a latch arranged to engage said latch arm to hold said toggle releasably in an underset position, means for

tripping said latch, manual means for moving said locking toggle into its underset switch closing position including a manually operable shaft disposed above and perpendicular to said operating shaft, and means operatively interconnecting said manually-operable shaft and the toggle member carried by said operating shaft, said toggle constituting an actuating toggle for moving said actuating mechanism to closed position.

55 4. An electric switch having the combination of switch mechanism, operating mechanism therefor including a horizontal operating shaft, a pair of angularly related arms constituting an operating bell crank fixed to said shaft, a rigid link connecting said switch mechanism with one of said arms, a horizontal actuating shaft, an actuating member fixed to said shaft and having oppositely directed arms, a link pivotally connecting one of said arms with the other arm of said operating bell crank, a switch closing mechanism operatively connected with said actuating member, means biasing said actuating member toward switch open position, a toggle having one end thereof pivotally connected with an arm of said actuating member and having its other end freely supported on said operating shaft, a latch arm carried by a member of said toggle, a latch arranged to engage said latch arm and hold said toggle releasably in an underset position, and means for electrically tripping said latch.

60 5. An electric switch having the combination of switch mechanism, operating mechanism therefor including a horizontal operating shaft having a pair of angularly related fixed arms constituting an operating bell crank, a link connecting one arm of said bell crank with said switch mechanism, switch actuating mechanism for said operating mechanism including a horizontal actuating shaft having an actuating member fixed thereto including oppositely directed arms, a rigid link pivotally connecting an arm of said actuating member with the other arm of said operating bell crank, a switch closing mechanism having an operative connection with said actuating shaft, a locking toggle for holding said actuating mechanism in switch closed position, said toggle having one end thereof pivotally connected with an arm of said actuating member and having its other end freely supported on said operating shaft, means to hold said toggle releasably in an underset position, and tripping means for said holding means.

65 6. An electric switch having a crank arm, a horizontal operating shaft having a pair of angularly related arms fixed thereto, a rigid link connecting one of said arms with said crank arm, a horizontal actuating shaft pivotally supported beneath and parallel with said operating shaft, an actuating member

carried by said actuating shaft having oppositely directed arms, a link pivotally connecting one of said arms with the other arm of said operating shaft, a locking toggle having one end thereof connected pivotally with an arm of said actuating member and having its other end freely mounted on said operating shaft, one of said toggle members having an angularly-related latch arm, a latch arranged 5 to engage said latch arm and hold said toggle releasably in an underset position, means for electrically tripping said latch, and manual means for closing the switch by the straightening movement of said toggle including a 10 manual operable shaft disposed adjacent said operating shaft, and cooperating means carried by said manually operable shaft and one of said toggle links for effecting the straightening of said toggle by the manual operation 15 of said shaft.

7. An electric switch having the combination of switch mechanism, operating mechanism therefor and switch opening and closing means for said operating mechanism including 20 a pivoted actuating member, a pivoted link constituting a rigid connection between said actuating member and operating mechanism for the conjoint movement of both between switch open and closed positions, a 25 switch closing mechanism having an operative connection with said actuating member, means to bias said actuating mechanism constantly into switch open position, means to hold said mechanism releasably in a switch 30 closing position against its bias including a locking toggle having a pair of toggle links, one of which is pivotally connected to said actuating member and the other of which is freely pivoted on said operating shaft, said 35 latter member having an integral depending latch arm, a latch arranged to engage said arm and hold said toggle releasably in an underset position, and means for electrically 40 tripping said latch.

45 8. An electric switch having the combination of switch mechanism, operating mechanism therefor, actuating mechanism for said operating mechanism including a pivoted actuating member having oppositely directed 50 arms, a rigid link pivotally connecting one of said arms with said operating mechanism, a locking toggle arranged to hold said actuating member releasably in switch closed position, said toggle having one arm thereof pivotally 55 connected with said actuating member and having at its other arm a hub which is pivotally connected with a fixed support, said other toggle member including an integral latch arm, a pivoted latch arranged to engage 60 said latch arm and hold said toggle in an underset position, means for electrically tripping said latch, and means for closing the switch manually through said toggle including a manually operable shaft having a pinion 65 gear thereon which is adapted to engage co-

operating gear teeth on the hub of said other toggle member.

9. An electric switch having a switch frame, switch mechanism carried by said frame, an operating face plate having a horizontal operating shaft, a lower horizontal actuating shaft, a pair of angularly related arms fixed to said operating shaft, means operatively connecting one of said arms with said switch mechanism, an actuating member carried by 70 said actuating shaft having forwardly and rearwardly extended arms, a rigid link pivotally connecting said forwardly extended arm with the other arm of said operating shaft, a switch closing mechanism carried by said face plate having an operative connection with the rearwardly extended arm of said actuating member, means for biasing said actuating member into a switch open position, means to hold said actuating member releasably in a switch closed position against said bias including a locking toggle having one end pivotally connected to an arm of said actuating member and having its other and upper end freely supported on said operating shaft, one of said toggle members having an integral latch arm, a pivoted latch arranged to engage said latch arm in the closed position of said actuating member, in which position of said actuating member said toggle is adapted 85 to occupy an underset position, and means for tripping said latch.

10. An electric switch comprising the combination of switch mechanism, switch operating mechanism, and opening and closing mechanism for said operating mechanism including a pivoted actuating member having oppositely directed arms, a rigid link pivotally connecting one arm of said actuating member with said operating mechanism, means for actuating said actuating arm, means biasing said member to switch open position, a locking toggle including a pair of links one of which is connected with said actuating member, a latch arranged releasably to hold said toggle in an underset position whereby to hold the switch closed, and means arranged to trip said latch, whereby to open the switch.

11. An electric switch including a switch frame, switch mechanism carried by said switch frame, an operating face plate having switch operating mechanism including an operating shaft having a forwardly extended arm, an actuating shaft, an actuating member having forwardly and rearwardly extended arms fixed to said actuating shaft, a rigid link pivotally connected at its one end to the arm of said operating shaft and at its other end to the forwardly extended arm of said actuating member, a switch closing mechanism operatively connected with the rearwardly extended arm of said actuating member, means to bias said actuating member into switch open position, means to hold said member releasably in switch 100 105 110 115 120 125 130

- closed position including a locking toggle comprising upper and lower pivotally connected links, said lower links having a pivotal connection with an arm of said actuating member, and said upper link being rotatably mounted on said operating shaft, a latch arm carried by one of said toggle links, a latch arranged releasably to hold said toggle in an underset position, whereby to hold the switch closed, and means to trip said latch.
12. Switch operating mechanism including an operating shaft having a forwardly extended arm, an actuating shaft, an actuating member having forwardly and rearwardly extended arms fixed to said actuating shaft, a rigid link pivotally connected at its one end to the arm of said operating shaft and at its other end to the forwardly-extended arm of said actuating member, means to bias said actuating member into switch open position, means to hold said member releasably in switch closed position including a locking toggle comprising upper and lower pivotally connected links, said lower link having a pivotal connection with an arm of said actuating member, and said upper link being rotatably mounted on said operating shaft, a latch arm carried by one of said toggle links, a latch arranged to hold said toggle in an underset position, whereby to hold the switch closed, means to trip said latch, and manually operable means to close the switch including a rotatable shaft having a driving connection with said upper toggle link, whereby to rotate said link about its pivotal support on said operating shaft and close the switch by said toggle.
13. In testimony whereof, I have signed my name to this specification.

CHESTER D. AINSWORTH.
